UNITED STATES PATENT OFFICE.

BENJAMIN E. GETCHELL, OF PLAINVILLE, CONNECTICUT, ASSIGNOR TO THE TRUMBULL ELECTRIC MANUFACTURING COMPANY, OF PLAINVILLE, CONNECTICUT, A CORPORATION OF CONNECTICUT.

ELECTRIC SWITCH.

Application filed September 4, 1926. Serial No. 133,722.

The main object of this invention is to provide a practical and dependable means for preventing the formation of an injurious arc in the opening movement of the switch 5 and for effectually snuffing out such minor arcing as may form.

Another object is to provide a snuffing means which will confine the arc laterally with respect to the blades and contacts and 10 thus prevent the jumping of the arc to adjacent blades or switch parts.

Another object is to provide an arc snuffing means particularly adapted for use in a double throw switch construction, and 15 which will also act to hold or retain the blades of a double throw switch in neutral position when the switch is off.

Another object is to provide an arc snuffing means with its parts so designed and proportioned that it will also automatically operate 20 to latch the switch in the on position, and assist in the opening movement of the switch after the switch has been manually moved 25 from the latched on position, and act as a suitable stop in the opening movement of the switch.

The invention is shown as applied in commercial practice to a three-pole, double-throw 30 enclosed switch of the knife blade type, but, obviously the invention may be used, in whole or in part, in different types of switches having one or more blades or different types of contacts.

The quick-break arrangement shown in 35 the drawings is fully described in my former Patent No. 1,483,846. This patent also shows the method of mounting a switch of this description in a box and providing it with an external operating handle.

40 My former Patents Nos. 1,407,852 and 1,473,574 disclose arc snuffing arrangements having some generally similar characteristics, but these constructions as shown are adapted only to single-throw switches and cannot be used in a double-throw construction.

The present invention consists of providing an insulating housing or arc snuffing rocker and pivoting the rocker to or adjacent the contact jaw of the switch and further 50 providing the blade of the switch with an insulating block, the rocker being provided with spring means tending to move the rocker over the top of the contact jaw and between the jaw and the blade and the block

on the blade co-operating with the rocker 55 to block the path of the arc as the switch blades are being opened. The blade is provided with rollers which bear upon the side plates of the rocker with a cam movement which moves the rocker out of the path 60 of the blade in the switch closing movement.

The rollers also co-operate with suitable shoulders on the side plates of the rocker to latch the switch in closed position.

The rollers also co-operate with another 65 part of the side plates of one of the rockers to form a stop for the switch when it is being moved to neutral position.

The rollers further co-operate with the side plates of a pair of oppositely disposed 70 rockers to hold or retain the switch in neutral position.

The spring pressure of the side plates upon the rollers assists in the opening movement 75 of the switch after the latching engagement of the rocker and rollers has been broken.

Fig. 1 is a front view of one form of construction showing a switch with three units, the circuit being closed with one set of contacts.

Fig. 2 is a side view of the same, showing 80 the supporting base in section.

Fig. 3 is a fragmentary sectional view on a larger scale showing the switch in the neutral or open circuit position.

Fig. 4 is a similar section and side view showing the switch closed at one side and about to be opened. This also shows in dot and dash lines parts of the switch in intermediate position.

Fig. 5 is a fragmentary end view showing 90 the method of supporting one of the shield members.

Fig. 6 is a detail end view of one of the 95 blades and parts carried by it.

Fig. 7 is an exploded perspective view showing one of the switch blades, one of the switch contacts, and a shield.

Fig. 8 is a front view on a reduced scale showing one form of casing with the interior 100 parts added.

Fig. 9 is a side view of the same.

The switch jaws or contacts 10 and 11 may be of any suitable type and are disposed opposite each other as is customary in 105 double throw switches. I have also shown fuses 12 and 13 which are ordinarily employed in switches of this type, but which are

- not material to this invention. Circuit terminals 14 and 15 are also provided as usual. The entire construction is mounted on an insulating base 16 of any suitable character.
5. The movable switch member 17 is preferably hinged at 18 to a standard secured to the base in the usual manner. Each switch member has two blades 19 and 20, the outer ends of which are adapted to co-act, respectively, with the stationary contacts 10 and 11. The switch may have any number of switch units such as 17, and they are preferably connected by a cross-bar 21 of insulating material. An operating crank 22 of any suitable type is supported in any suitable manner, as for instance, in the opposite sides of the box 23, and provided with an external handle or lever 24. The box is provided with a cover 25 of any suitable type.
20. The switch is preferably of what is known as the quick-break type. A bracket 26 is secured to the cross-bar 21 and supports the hinged arms 27 and 28 which are normally drawn toward each other by the spring 29.
25. The bracket is provided with projections 30 and 30' which serve as stops for the arms 27 and 28, respectively. When the crank 22 is moved in the direction of the arrow of Fig. 4, it tilts the arm 28 so that it engages the shoulder 30' and places the spring 29 under tension. Continued movement of the crank 22 flexibly moves the switch member 17 until the blade 19 is free from the contact jaw 10, whereupon the spring 29, through 35 its connection with the arm 27, suddenly throws the switch member 17 so as to separate the blade 19 from the contact 10 with a snap action or a quick-break, as it is sometimes called.
40. A shield member is formed of insulating material and preferably consists of two side plates 31 and 32 with an intervening barrier 33. The shield is hinged or pivoted on the pin 34 which extends through the contact member 11. It will be understood, of course, that the shield member 32' at the right of Fig. 4 is constructed in the same manner as the one illustrated at the left in Fig. 7. Springs 35 and 36 on the ends of the pin 34 engage the plates 31 and 32 so as to press the shield toward the center of the switch. The pin 37 serves as an abutment for the lugs 38 when the parts are in the position shown at the left in Figs. 3 and 4.
55. The switch blade 20 is provided with projections 39 on opposite sides which are preferably in the form of rotatable rollers adapted to roll along the curved edges 40 of the shield. Each blade such as 20 is provided with an insulating block 41 on its lower edge leaving the outer end of the blade free to engage the stationary contact 11. The shield plates 31 and 32 are hinged on opposite sides of the contact 11, and a groove 42 is left between them so as to allow for the movement of the ends of the switch blades 20 and the insulating block 41. The lower edges of the shield are cut away so as to provide a shield 43 adapted to engage the projecting rollers 39 when the switch is in the closed circuit 70 position.
- In the normal open circuit or neutral position of Fig. 3 the two spring-pressed shields serve to resiliently hold the switch member 17 in the central position. When it 75 is desired to close the switch, the member 17 is tilted to the right, as viewed in Figs. 3 and 4, whereupon the projecting rollers 39' roll or slide along the curved edge 40' of the shield 32' and force the shield out of 80 the way of the blade 19 which is then allowed to engage the contact 10. When the blade 19 is entirely or fully closed against contact jaws 10, the shoulder 43' on the shield 32' presses down against the projection 39' and thus holds the switch member in the closed circuit position.
85. When it is desired to open the circuit, the crank 22 is moved in the direction of the arrow of Fig. 4 as above mentioned. The projection 39' sliding along the shoulder 43' tilts the shield 32' out of the way of the blade 19 and the blade is allowed to leave the contact 10. As the tip of the blade leaves the contact, the shield carrier 33' moves across the outer end of the contact 10 to cut off any arc which might tend to follow. The insulating block 41' on the lower edge of the blade 19 prevents the arc from traveling along the lower edge of the blade. 90 The channel-like construction of the shield confines any arc which is formed between the walls of the shield and the stop 41' so that the arc cannot travel laterally to any other conducting part or any adjacent wall 95 of the box. It will also be noted that the shoulder being spring-pressed, tends to assist in the opening movement by its pressure against the projections 39'. Obviously, the operation of closing the circuit through the 100 blade 20 in contact with jaws 11 would be effected in the same manner as closing the blade 19 against the jaw 10 and the opening of the circuit through blade 20 and contact 11 would also correspond to the action above 105 described.
110. I claim:
1. In a switch, a stationary contact, an insulating shield hinged thereto and having a cam edge and a hinged blade having a roller adapted to slide along said cam edge and move said shield as the switch is closed. 115
  2. In a switch, a contact, a spring pressed insulating shield hinged adjacent thereto, a hinged blade having a projection engaged by said shield to hold the switch closed. 120
  3. In a switch, a contact, a spring pressed insulating shield hinged thereto, a stop for said shield and a hinged blade adapted to retract said shield and adapted to be assist- 125

ed toward the open position by said shield.

4. A switch including a contact, a grooved insulating shield hinged in co-operating relation therewith, a hinged blade for said contact, and an insulating block on the edge of the blade adapted to move into the groove of said shield.

5. In a double throw switch, hinged blades, stationary contacts therefor, a spring 10 pressed insulating shield co-acting with each contact and mounted to move with and assist in the opening movement of the switch after the initial manual opening movement of said blades.

15 6. In a double throw switch, a pair of contacts, a hinged member having a blade for each of said contacts and spring pressed insulating shields co-acting between each blade and its contact and having means for 20 pressing against said blades to yieldingly hold them closed.

25 7. A switch construction including a stationary contact, a movable blade for engagement with said contact, an insulating shield having operable connection with said contact, spring means to force said shield between said contact and said blade in the opening movement of said blade and roller means carried by said blade for moving said shield away from the path of said blade in the closing movement of said blade.

30 8. A switch construction including a stationary contact, a movable blade associated with said contact, an insulating shield associated with said contact and adapted to move between said contact and said blade in the opening movement of said blade, a spring tending to move said shield into said interposed position, means carried by said 40 blade to move said shield away from the path of said blade in the closing movement of said blade, a groove in said shield and an insulating member carried by said blade to cooperate with said groove.

45 9. A switch construction including a stationary contact, a movable blade associated with said contact, an insulating shield asso-

ciated with said contact and adapted to move between said contact and said blade in the opening movement of said blade, a 50 spring tending to move said shield into said interposed position, means carried by said blade to move said shield away from the path of said blade in the closing movement of said blade, a groove in said shield and an 55 insulating member carried by said blade to cooperate with said groove to block the path of the arc in the opening movement of the blade.

10. A switch construction including a stationary contact, a movable switch blade for engagement with said contact, a movable insulating shield having a groove, spring means for moving said shield between said contact and said blade in the opening movement of said blade, means carried by the blade for moving said shield away from the path of said blade in the closing movement of said blade, an insulating member carried by said blade to cooperate with said shield 70 and said groove to block the path of the electric arc in the opening movement of said blade.

11. In an electric switch the combination of a stationary contact, a hinged blade having a movable end adapted to engage said contact, an insulating shield hinged adjacent said contact on an axis substantially parallel to the axis of said blade, a spring tending to press said shield toward said 75 blade, said blade having a projection adapted to engage an edge of said shield in the circuit closing movement of said blade and said shield having a shoulder for engaging said blade to yieldingly hold it in its closed 80 circuit position.

12. An electric switch comprising a hinged blade having a movable end, a contact adapted to be engaged thereby, a grooved shield hinged adjacent said contact 85 and an insulating member carried by one edge of said blade between its ends and adapted to move in the groove of said shield.

BENJAMIN E. GETCHELL.
